UNITED STATES PATENT OFFICE.

PHILIP GANZHORN, OF WASHINGTON, ILLINOIS.

STIRRUP FOR RIDING-SADDLES.

SPECIFICATION forming part of Letters Patent No. 281,861, dated July 24, 1883.

Application filed May 2, 1883. (No model.)

To all whom it may concern:

Be it known that I, PHILIP GANZHORN, of Washington, in the county of Tazewell and State of Illinois, have invented a new and Improved Stirrup, of which the following is a full, clear, and exact description.

My invention consists of a toe-guard and tilting plate, contrived for insuring certain and ready escape of the feet of the rider from the stirrups when thrown from the horse, to prevent being caught therein and dragged along the ground; and my invention consists, also, of an improved spur attachment to the stirrup, all as hereinafter fully described.

Reference is to be had to the accompanying drawings, forming part of this specification, in which similar letters of reference indicate corresponding parts in all the figures.

Figure 1 is a sectional elevation of my improved stirrup. Fig. 2 is a plan view of the same, inverted, showing the spur attachment applied to the bottom of the stirrup. Fig. 3 is a cross-section on the line *xx* of Fig. 2; and Fig. 4 is a perspective view, showing the spur attachment applied to the side of the stirrup.

I propose to connect a thin strip, *a*, of metal, to the top *b* of the yoke at *c*, which is the center of the back of said top of the yoke, and also connect said strip by its other end to the center of the cross-bar *d*, which extends from side to side *e* of the yoke at the front of the bottom plate *f*, to form a toe-guard, along up which the toe of the foot will swing for escaping from the stirrup, when the foot rests on a foot-plate, *h*, which I pivot to the rear end of the bottom plate *f* at *i*, in connection with the aforesaid toe-guard, *a*, thus providing a simple and efficient means of insuring the escape of the feet of the rider in case of falling from the horse. In order that the foot may rest securely and comfortably on the bottom plate *h*, I pivot the plate nearly under the ankle-joint of the rider's foot—that is, about one-third the length of the plate from its rear end. At the same time I provide the bottom piece *f* for the forward part of plate *h* to rest on, and I hang the stirrup to its strap at a point centrally over the bottom piece *f*. This locates the pivot *i* about one-third the length of the foot-plate to the rear of the vertical line of the stirrup-strap, thus causing the ball of the foot to rest on the plate at a point in

front of its pivot, where the plate is supported by the bottom piece. In advance of this toe-guard I arrange the usual mud-guard, *j*, pivoting it to the top of the yoke at *k*. Under the bottom plate *f*, or upon the inner side, *e*, of the yoke, I propose to arrange a spur consisting of two pointed wires, *m*, attached to a short socket, *n*, which is connected to a plate, *o*, to be detachably connected to the bottom of the stirrup by sliding in grooved cleats *p*, and fastening with a set-screw, *q*, with which pointed rods there is a guard, *s*, attached to the end of a sliding rod, *t*, and sliding on the said pointed rods *m*, the sliding rod *t* having a spring, *u*, that pushes the guard *s* forward to the points of the rods *m*, to prevent them from taking effect when not intended to, but yielding readily when the rider thrusts the stirrup against the body of the animal, and allowing the points to prick him more or less, according to the force of the thrust, the said points *m* and guard *s* projecting sufficiently beyond the side of the stirrup to enable the points to have contact with the animal's body unobstructed by the side *e* of the yoke of the stirrup. The spring *u* is arranged in a tubular case, *v*, which is connected to the ear *w* of plate *o*, and extends into socket *n*, said case *v* having a slot along it, in which a bit, *x*, attached to the rod *t* slides to prevent the guard from escaping from the points *m* by contact with the ear *w*.

To connect this spur device to the side of the stirrup, as represented in Fig. 4, which it may be preferred to do in some cases, I make a triangular base, *y*, for the support of the grooved cleats *p*, in which to slide the plate *o*, on which the spur device is mounted, connecting said base *y* to the inside of the yoke of the stirrup with the point of said base forward, so that the spur-points will project obliquely toward the body of the horse, to be made to take effect by correspondingly inward and backward movements of the stirrup by the rider. The contrivance of the spur device itself may be the same for this location as for the other, except as to the base *y*, as aforesaid, using the same binding-screw, *q*.

I propose, in practice, to make the yoke consisting of top *b*, sides *e*, the bottom plate, *f*, and the foot-plate *h* of wood, the mud-guard *j* being preferably made of leather; and I will

connect the yoke to the strap z by the metallic loop a' , having the stud b' , to which the yoke, re-enforced at the top by the wooden saddle or back piece c' , is swiveled, so as to turn freely, as stirrups are commonly arranged.

Having thus described my invention, I claim as new and desire to secure by Letters Patent—

1. The combination, with a stirrup having a frame consisting of a yoke and bottom suspended by a strap, of a foot-plate fulcrumed in the rear of its middle to the rear of said bottom, at a point to the rear of the line of suspension, and resting on the bottom forward of said line, as and for the purpose specified.
- 15 2. The combination, with a stirrup having a frame consisting of a yoke and bottom suspended by a strap, and a foot-plate within the frame, fulcrumed thereto in the rear of its line of suspension, of a strip of metal secured at one end to the yoke and at the other end to the bottom in a curve approximating an arc of a circle whose center is the fulcrum of the front plate, as shown and described.

3. A stirrup consisting of a yoke and bottom suspended by a strap having grooved cleats, substantially as described, in combination with a spur provided with a plate adapted to fit said cleats, and a set-screw for binding the spur to the stirrup, as shown and described.

4. The spur-points m , yielding guard s , the spring u for the guard, and the socket n and tube v , attached to the plate o , and the plate o , detachably connected to the stirrup, substantially as described.

5. The spur-points m , yielding guard s , the socket n , tube v , spring u , stop x , and the supporting-ear w , attached to plate o , and the said plate attached to the stirrup by the cleats p and binding-screw q , substantially as described.

PHILIP GANZHORN.
